SUPPORT FOR PIVOTED SEATS

Henry P. Nordmark, Grand Rapids, Mich., assignor to American Seating Company, Grand Rapids, Mich., a corporation of New Jersey

Application May 5, 1938, Serial No. 206,102

4 Claims. (Cl. 155—85)

The present invention relates to chairs having turnably mounted seats, and its object is to provide improved means for supporting such a seat in its lowered position of use.

This and any other and more specific objects hereinafter appearing are attained by, and the invention finds preferable embodiment in, the illustrative chair structure particularly described in the body of this specification and illustrated by the accompanying drawings, in which:

Figure 1 is a sectional view of a side portion of a chair's seat, its pivotal mounting and supporting means with connected parts, taken on line 1—1 of Figures 2, 7 and 8;

Figure 2 is an inner side view thereof, shown partially in section taken on line 2—2 of Figures 1 and 4;

Figure 3 is a sectional view of parts of the same taken on line 3—3 of Figure 2;

Figure 4 is a sectional view of parts of the same taken on line 4—4 of Figures 2 and 6;

Figure 5 is a transverse sectional view of parts of the same taken on line 5—5 of Figure 4;

Figure 6 is a perspective interior view of the same;

Figure 7 is a view similar to Figure 2 but showing the seat in raised position and partially sectioned on the same line 2—2 of Figure 1.

Figure 8 is an elevational side view of a chair embodying my invention.

In these drawings a theatre chair is shown having a seat 1, leg standards 2 at its sides and a horizontal spindle 3 on the standards whereon the seat is supported for turning movement thereon to horizontal lowered or use position seen in Figures 1, 2, 7 and 8 and to raised position.

Only one side portion of the seat, the standard and the parts of the chair adjacent that side are illustrated in Figures 1—6, both of the chair's opposite side portions and the adjacent parts being desirably identical as indicated in Figures 7 and 8.

In the embodiment of the invention illustrated by these drawings, the spindle 3 extends through the bearing 4 in a metal plate 5 extending in cup form outwardly through an opening in the side 6 of the chair's metal base frame or "pan" 7 and is held in place by rivets 8. A toothed segment 9 is fixed on the outer end of this spindle concentrically therewith. A rigid bar, the flat plate 10, has an elongated slot 11 slidably bearing on the pin 12 extending therethrough and mounted on the seat's side 6. This bar has an elongated opening 13 parallel with said slot and

provided at one of its sides with a rack 14 meshing with the segment in said opening.

As the seat is turned on the spindle toward its lowered (horizontal) position of use, the bar is slid by this turning movement rearwardly on the seat until it is stopped by the limit of the mutual meshing engagement of the rack and the segment or by the abutting of the end 15 of the slot on the pin 12, and preferably by both these means, in which stopped position of the bar the seat is supported thereby in lowered position; and as the seat is turned upwardly toward its raised position, the bar is slid forwardly-upwardly.

To yieldingly hold the seat against falling from raised position friction means are provided, the friction plates 16 pressed by the four-arm cup spring 17 between disks 18 through which the pin 12 extends.

It will be seen that in the illustrated construction the bar (i. e., its rack 14) engages the spindle (i. e., its segment 9) eccentrically of the spindle.

It will also be seen that the segment 9 and plate or bar 10 with associated parts are housed in the hollow seat which protects them from dirt and injury and prevents the clothing of the occupant from being engaged between the meshing teeth of the segment and plate or bar.

The spindle, as illustrated, comprises a tubular part 19 on which the seat turnably bears, this part extending tightly through an opening in a plate 20 and having a ring 21 in which its inner end is riveted or upset, said ring being tightly held at its opposite flat sides between said plate 20 and a bracket 22 secured on the side of the standard and having downwardly converging grooves 23 in which the correspondingly shaped edges 24 of this plate are wedgingly received; the spindle comprising also a cross-sectionally angular (square as shown) part 25 in the tubular part, with its angles 26 fitting into the tubular part as shown in Figure 5 to hold these parts against relative turning movement. It will be seen that this spindle is very rigid and very stably supported.

The outer end of the spindle's part 25 extends tightly through square openings in the segment and in the inner disk 27, this part 25 being round at 28 near its outer end and received in the round opening of the outer disk 29. The outer end of said part 25 has a head 30 whereby the disks 27, 29 are held in place with the segment therebetween. This segment in the particular construction illustrated is formed of three identical

flat members 9 as indicated in Figures 1 and 4 welded together.

In this particular construction coiled springs 31 pressing between the inner surface of the sides of the seat and the disks 27 serve to resiliently balance the seat between the standards.

The invention being intended to be pointed out in the claims, is not to be limited to or by details of construction and arrangement of the particular embodiment thereof illustrated by the drawings or hereinbefore described.

I claim:

1. In a chair of the class described: a leg standard having a fixed horizontal spindle with a toothed segment fixed thereon; a seat turnable on the spindle to lowered use position and to raised position; and a bar slidable on the seat forwardly-rearwardly thereof, having a forwardly-rearwardly elongated opening with a toothed rack at one side thereof wherewith the segment in the opening meshes in the seat's turning movement, the bar being slid, by the seat's downwardly turning movement, to a position wherein one end of the opening engages the segment therein for supporting the seat in its lowered use position.

2. In a chair of the class described: a leg standard having a fixed horizontal spindle with a toothed segment fixed thereon; a seat turnable on the spindle to lowered use position and to raised position; and a bar slidable on the seat forwardly-rearwardly thereof, having a forwardly-rearwardly extending toothed rack wherewith the segment meshes in the seat's turning movement, the rack having a terminal end engaging the segment in one extreme slid position of the

bar, the bar being slid to its said extreme position by the seat's downwardly turning movement to use position, for supporting the seat in its said position.

3. In a chair of the class described: a leg standard having a fixed horizontal spindle with a toothed segment fixed thereon; a seat turnable on the spindle to lowered use position and to raised position and having a stop; and a bar slidable on the seat forwardly-rearwardly thereof and having a forwardly-rearwardly extending toothed rack wherewith the segment meshes in the seat's turning movement, the rack having a terminal end engaging the segment in one extreme slid position of the bar, the bar being, by the seat's downwardly turning movement to use position, slid to its said extreme position wherein the rack's said terminal end engages the segment and the bar abuttingly engages said stop, for supporting the seat in its lowered use position.

4. In a chair of the class described: a leg standard having a fixed horizontal spindle with a toothed segment fixed thereon; a seat turnable on the spindle to lowered use position and to raised position and having a chamber into which the spindle extends and in which the segment is housed; a bar housed in the chamber, slidable on the seat forwardly-rearwardly thereof and having a forwardly-rearwardly extending rack wherewith the segment meshes in the seat's turning movement; and means in the chamber for limiting the bar's sliding movement to an extreme position wherein the seat in its lowered use position is supported on the bar.

HENRY P. NORDMARK.
